BILFOLD

Ervin Kery, West Bend, Wis., assignor to Enger-Kress Company, West Bend, Wis., a corporation of Wisconsin

Continuation-in-part of design application Ser. No. 4,630, Nov. 14, 1966. This application Jan. 30, 1968, Ser. No. 10,782

Term of patent 14 years

U.S. CL. D87—3
Int. CL. D3—02

Fig. 1
Fig. 3
Fig. 2
FIG. 1 is an elevational view of a billfold showing my new design, the billfold being open and viewed from the inside;

FIG. 2 is a plan view showing the billfold when the left-hand side has been folded over, the other half of the outer side being the same as that shown in FIG. 2; and

FIG. 3 is an edge view of the open billfold viewed from above FIG. 1.

The characteristic feature of my design resides in the slotted effect separating the right and left hand inside panels in substantially the configuration disclosed.

This is a continuation-in-part of design application Ser. No. D. 4,630, filed Nov. 14, 1966 and now abandoned.

I claim:

The ornamental design for a billfold, as shown and described.
